PANEL

Philip Zalkind, New York, N. Y.

Original application October 19, 1935, Serial No. 45,708. Divided and this application October 11, 1938, Serial No. 234,405

5 Claims. (Cl. 189—53)

My invention relates to panels, and more particularly relates to plug shaped, folding panels made of sheet and/or fibrous material such as corrugated board, container board, fiber board, sheet metal and the like, and is a division of my co-pending application Serial No. 45,708 filed October 19, 1935.

My panel comprises a substantially flat member provided with an outstanding hollow, plug shaped reinforcing member secured to the periphery of the panel. In the preferred embodiment of my invention, I fold the panel with its peripheral reinforcing member from a single blank of suitably shaped and scored sheet material.

The hollow outstanding extension which forms the plug, not only greatly increases the strength and rigidity of the panel but also provides a resilient bead forming a part of the panel and a complete boundary for the panel.

I have found that a panel constructed according to my invention may be used for many purposes. In my copending application Serial No. 739,962 filed August 15, 1934, I have shown my reinforced panel in several modifications applied as a door for a collapsible cabinet, and the present application is a continuation in part of the above mentioned copending application.

Other uses to which my reinforced panel is applicable, are as a top for a collapsible table; as a top for an inexpensive desk; as a cover for a collapsible clothes hamper; as a tight sealing end for a container, such as a dust proof collapsible transfer file or as an end seal for an ice-cream shipping container. I recite the above uses as examples only, as my panel in its several modifications may be used for many other purposes. In my several copending applications filed coincidentally with my parent application and co-pending with this application and entitled: Drawer, Serial No. 45,711; Three sided casing, Serial No. 45,714; Predetermined bend line, Serial No. 45,710, and Container fastening means, Serial No. 46,316, all filed October 19, 1935, I have shown several forms of filing cases and drawer to which the panels of the present application may be adapted.

The preferred size and shape of my plug reinforced panel will vary with the particular construction in which it is employed. Thus when it is used in large horizontal panels such as are required for table and desk tops, the reinforcements will be larger than when it is used as an end for a dust proof transfer file. Also when used for instance as a table top, the outstanding

reinforcements serve principally for their structural strength and rigidity, acting as box girders to carry the load of the panel back to the table supports; while when used as an end for an ice-cream container, a dust proof cabinet door, etc., the resilient properties of the reinforcement act to produce a tight seal between the panel and the opening which the panel is designed to close.

Accordingly, certain objects of my invention are to provide a novel construction of a panel sheet material, such as an impervious substance which may be folded for shipment; which has structural strength and rigidity; which may be used as a closure member for an opening to effectively seal the opening; which has ruggedness to withstand wear and tear; which has a pleasing appearance; and which is inexpensive to construct and transport.

There are numerous other objects of my invention which will become evident in the course of the detailed description which follows in connection with the drawings in which:

Figure 1 is a developed blank of one form of my invention.

Figure 2 is a perspective view, partly broken away, showing the panel from blank of Figure 1.

Figure 3 is a developed blank of a modified form of my panel.

Figure 4 is a perspective view, showing the panel from the blank of Figure 3.

Figure 5 is a developed blank of a corner member for use with the panel of Figure 4.

Figure 6 is an enlarged cross section of the plane 6—6 of Figure 4.

Figure 7 is a developed blank of a further modified form of panel.

Figure 8 is a perspective view, partly broken away, of a panel formed from the blank of Figure 7.

Figure 23 is a developed blank of a further modified panel.

Figure 24 is a cross section in perspective showing panel formed from blank in Figure 23.

Figure 25 is a perspective view of a modified panel shown in blank in Figure 26.

Figure 26 is a developed blank of Figure 25.

In Figures 1 and 2, I have shown a panel for use as a door for a cabinet such as I have shown in my copending application Serial No. 739,962. As shown in Figures 1 and 2, the blank 1 has parallel scored lines as 2a, 2b, 2c, and 2d on one side; 3a, 3b, 3c, and 3d on the corresponding opposite sides; 4a, 4b, 4c, and 4d on the top; and 5a, 5b, 5c, and 5d at the bottom. Reinforcements of square cross section are formed from these scored portions by turning the sections on their score lines.

The blank 1 is divided by the scores 2a, 3a, 4a, and 5a into the main panel 6, and the two side flaps 7 and 8, and the two end flaps 9 and 10.

Each of these flaps folds over to form a hollow, resilient, rectangular reinforcing member along one of the four edges of the main panel 6. Thus the reinforced edge 7 shown in Figure 2 is formed from the flap 7 of Figure 1 by bending the flap 7 along the score lines 2a, 2b, 2c, and 2d. After bending the reinforcements into position as shown in Figure 2 they may be secured in place by any suitable means, as for instance proper adhesive means. Thus the portions 7a, 8a, 9a, and 10a respectively of the flaps 7, 8, 9, and 10 may be pregummed, so that by moistening these flap portions they will adhere to the back of panel 6 when they are folded into position.

A series of slots 11a, 11b, and 11c provide means for attaching a hinge portion to the door member, with the fastening means for the hinge within the side reinforcing member. The opening 11d provides means for mounting a handle within the other side reinforcement with the handle protruding through the opening 11d.

While as shown the reinforcing members are shown as being rectangular in cross section, they may be slightly sloped inwardly on their outer portion, so that the inside of the door is somewhat smaller than the outside of the door, producing a wedge construction. If then the inside of the door is slightly narrower and shorter, and the outside of the door is slightly wider and taller than the door opening, when the door is closed, it is held closed by the wedge construction, and the opening will be tightly sealed with the resilient reinforcement closely conforming to the door opening.

In Figures 3, 4 and 6, I have shown a modified

form of my invention. This form is also applicable as a door. The blank for the door is shown in Figure 3. The distinction between this blank and the blank described in connection with Figure 1 is that the material is cut away as at 1b, 7c, 7d and 7e; 8b, 8c, 8d, and 8e; 9b, 9c, 9d, and 9e; and 10b, 10c, 10d, and 10e so that when the flaps are folded along the score lines, the reinforcing members will meet each other at the corners in miter joints, while the blank of Figure 1 provides square butt joints. Slots 11a', 11b' and 11c' of reinforcing flap 1 register with hinge slots 11a, 11b and 11c respectively of area 6 when the reinforcement is folded up and likewise cut-out 11d' of flap 8 registers with handle cut-out of 11d of member 6.

As was described in connection with the blank of Figure 1, the hollow reinforcing members may be secured in place by means of adhesive applied to the outer portions 7a, 8a, 9a, and 10a respectively of the flaps 7, 8, 9, and 10; or other securing means such as rivets may be used. Furthermore, the outer portions 7a, 8a, 9a, and 10 may be omitted and the reinforcing member secured in place by a tape.

In Figures 4, 5, and 6, I have shown a novel construction of a corner member, which not only strengthens the corner, but aids in securing the hollow reinforcements in place. These corner members may be made of metal stampings or of specially treated stiff paper board. As shown in Figure 5, the blank 12 is cut into a right angle shape at one end, as at 13 and is separated into a plurality of sections by suitable score lines. One side of the angle is separated from the other by means of the slot 14, and the end opposite 13 has a portion cut away as at 15.

When the blank is turned on the score lines the sections 16 and 17 are turned to engage the sides of the corner, as illustrated in Figure 4. Sections 18 and 19 are of the width as the distance from the outer to the inner side of the corner being reinforced, so that the sections 20 and 21 engage the inner corner sides, and sections 22 and 23 are turned into a position between the hollow reinforcing member and the main panel, as shown in Figure 6. Such a corner reinforcing, while adding considerably to the strength, will also be relatively cheap as no material is wasted since the next succeeding stamping will fit adjacent to the angle edge 13.

While I have described the corner reinforcements in connection with the blank of Figure 3, they can also be used with the blank of Figure 1. Also the panels from the blanks of Figure 1 and Figure 3 have been described as doors, and the slots 11a, 11b, and 11c have been shown for securing the door hinges with the hollow reinforcement; but it will readily be understood that the hinge slots may be omitted and the same general form of panel used for other purposes. As an example of other uses, the panel of Figure 4 could be used as a desk top in connection with my collapsible filing cases and drawers. Thus two low stacks of my casings would serve as desk supports with drawers on each side of a central opening, the drawers in each stack being interlocked to each other, as shown in my copending application Serial No. 693,841 and the top being interlocked to each stack of casing. For this adaptation sections 20 and 21 of the corner reinforcements may be provided with interlock slots as shown on the casing reinforcements in Serial No. 693,841 referred to above. A further use for the panels described above is as a top for a fold-

ing table, in which the legs could be suitably hinged to the corner reinforcements and adapted to fold within the space between the hollow edge reinforcements.

Now referring to Figures 7, 8, 9, and 10, I have shown a further modification in which the hollow edge reinforcement is spaced a short distance from the edge of the panel, thus providing a lip or flange around the edge of the panel and extending outwardly from the hollow reinforcement of the panel. Moreover, in these figures, the blank is so arranged that the edge reinforcements interlock with each other in such a manner that when two of these reinforcements are properly secured, the other two reinforcements are also held in place.

In these figures the blank 30 has the double score lines 31a, 31b; 32a, 32b; 33a, 33b; 34a, 34b; which define the main panel 35. These double scores are preferably of the type disclosed in my copending application entitled: End fold casing Serial No. 45,713 and filed coincidently with my parent application and copending with this application, now Patent 2,088,315, patented July 27, 1937. Extending from the main panel are the flaps 36, 37, 38, 39, which form the flanges around the panels and the hollow reinforcing members. Each of the flaps is provided with a number of parallel score lines which divide each of the flaps into a number of sections. Thus flap 36 has the score lines 31c, 31d, 31e, 31f, which define the sections 36a, 36b, 36c, and 36d, and 36e. Each of the flaps 37, 38 and 39 are similarly provided with score lines which define similar sections of the respective flaps.

It will be noted in Figure 7, that the flap sections 36a, 37a, 38a and 39a terminate in a line at 45° to the score lines and that these 45° lines start at the ends of the double scores which define the main panel 35. Thus when the flaps are folded over as shown in Figure 8, the sections 36a, 37a, 38a and 39a form a flange around the panel 35 and meet each other in miter joints at the four corners.

The flap 36 is cut back at the sides starting at section 36b by a distance equal to the thickness of the blank stock, as shown at 36g and 36h. Flap 38 is cut back in a similar manner. Section 36c, which in the folded position is parallel to the panel 35, is provided with slots 36i and 36j of a length equal to the width of sections 37c and 39c, and of any desired width. The purposes of these slots will be more fully explained later.

Now referring to the flaps 37 and 39 which are like each other and which will be described by referring specifically to flap 39. Flap section 39b is of the same length as the shorter of the two scores of section 39a. Centered on this section are the sections 39c, 39d, and 39e, the two last mentioned sections being shorter than section 39b by the width of section 36c plus the width of section 38c. The length of section 39c exceeds that of 39d or 39e by the width of slot 36j plus the width of slot 38i, thus providing the extensions 39k and 39l each equal to the width of the slots 36j and 38i. The section 39e is provided with the tabs 39m and 39n, preferably of sheet metal, and secured to the flap by means of prongs or rivets. Between the double score line 34a and 34b, are the two slots 39o and 39p each spaced relative to the center line of the panel the same distance as are the tabs 39m and 39n. These slots are slightly larger than the cross sectional dimensions of the tabs 39m and 39n.

In setting up the panel, the flaps 36 and 38 are

first turned into place on their respective score lines. Then either flap 37 or flap 39 is turned into place. The following description is referred to the flap 39, though it could apply in a like manner to the flap 37.

When the flap is turned on its score lines the tabs 39m and 39n will enter the slots 39o and 39p respectively. These tabs are then pulled tight which will bring the entire structure into position, and are then turned over the flange 39a as is clearly shown in Figures 8 and 9.

It will be noted that in this position the end extensions on flap section 39b effectively cover one end of each hollow structure formed by the flaps 36 and 38 and fitting respectively into the cut away portions 36h and 38g previously described. Also the extensions 39k and 39l of section 39c fit into the slots 36j and 38i respectively locking over the upstanding portions 36d and 38d at their end where they meet the slots 36j and 38i. The flap 37 operates in the same manner, so that the entire structure is effectively and simply locked in its set up position by the tabs on members 37 and 39. While two of these tabs are shown on each flap 37 and 39, the number may be varied as required. Thus on a short panel only one tab may be needed, while on a long panel more than two tabs may be required.

On the panels so far described, the reinforcing members have been quadrangular in cross section. In Figure 11, I have shown a form of blank from which a panel having reinforcing members of triangular cross section may be produced. In the Figure 40 represents the blank of material having the parallel score lines 41a, 41b, 41c; 42a, 42b, 42c and the score lines 43a, 43b, 43c; 44a, 44b, 44c, perpendicular thereto.

The scores 41a, 42a, 43a, 44a define the main panel 45, which may be provided with the handle 46 shown of the type used with my filing drawer and disclosed in my Patent 1,946,516. Extending from the main panel are the flaps 47, 48, 49, and 50. These flaps are divided by their respective score lines into the sections 47a, 47b, 47c; 48a, 48b, 48c; 49a, 49b, 49c; and 50a, 50b, 50c.

The blank of Figure 11 may be used with a base member such as shown in Figure 13 or Figure 14. In Figure 12 there is shown the blank of Figure 11 assembled in connection with the base member of Figure 14.

The base member of Figure 13 comprises a blank of sheet material 52 of the same dimensions as the finished panel. This blank has the opening 51 adapted to register with the handle 46 when the panel is in set up position. Along the edges of sheet 52 are the strips of metal 53 having a predetermined bending line 54 as described in my copending application Serial No. 693,841 filed Oct. 16, 1933, and the continuation thereof entitled: Predetermined bend line, Serial No. 45,710 and filed coincidently with my parent application and copending with this application. In assembling the panel with this base member, the blank 40 is bent upon its score lines and is superposed upon the base 52. The metal strips 53 are then bent on their predetermined bending lines 54 as shown in section in Figure 16. This securely unites the folded blank and the base member to form an integral structure.

When the folded blank 40 is used with the base member of Figure 14, as shown in perspective in Figure 12 and in cross section in Figure 15, the handle member 46 may be omitted, even where a handle is required, as the base 55 as shown is provided with the handle 56.

Base member 55 is preferably of construction similar to that of the metal front disclosed in my copending application entitled: Drawer Serial No. 45,711 and filed coincidentally with this application. It comprises the metal panel 55 having the integral frame 57 drawn from the metal of the panel 55. The frame 57 has the opening 58 in its center and this opening 58 has the flanges 59a, 59b, 59c and 59d at each of its edges. These flanges are of substantially the same height as the depth of the frame 57. Flanges 59a and 59c are provided with a slot 60a and 60c respectively for the bent wire handle 56. Around the edges of the panel 55 are the U shaped flanges 61a, 61b, 61c and 61d. Before setting up the assembled panel, these flanges are somewhat open.

In setting up the panel in connection with base 55 the blank 40 is bent on its score lines, and section 47c is inserted within flange 61b. Similarly section 49c is inserted within flange 61d. Sections 48c and 50c are then inserted respectively into flanges 61c and 61a. The flanges are then bent down to clinch their respective flap sections as clearly shown in Figure 15. This not only firmly unites the two members into an integrated structure; but also the panel 45 being held against the outstanding edges of flanges 59a and 59c acts to retain the handle 56 in the slots 60a and 60c.

In Figures 17, 18, and 19, I have shown a modified form of panel with reinforcing members of triangular cross section, but differing from the panel of Figure 11 in that the blank of Figure 17 forms a complete structure without a separate base member. In this figure 70 represents the blank of material having the parallel score lines 71a, 71b, 71c, 71d, 71e; 72a, 72b, 72c, 72d, 72e; and the score lines 73a, 73b, 73c, 73d, 73e; 74a, 74b, 74c, 74d, 74e perpendicular thereto.

The double score lines 71a, 71b; 72a, 72b; 73a, 73b; and 74a, 74b define the main panel 75. Extending from the main panel are the flaps 76, 77, 78 and 79. These flaps are divided by their respective score lines into the sections 76a, 76b, 76c, 76d; 77a, 77b, 77c, 77d; etc.

If the panel such as that shown in Figure 17 is to be used as a door it may be provided with the slots 11a, 11b, and 11c for attaching a hinge portion to the door member, with the fastening means for the hinge within the side reinforcing member. The opening 11d provides means for mounting a handle within the outer side reinforcement with the handle protruding through the opening 11d.

Referring to the flap 78. The section 78a forms a flange as shown in Figures 18 and 19. The section 78b forms the vertical member of the reinforcement, section 78c forms the sloping member; and section 78d forms a reentrant leg, which is preferably of sufficient length to extend between the panel member 75 and the flange member 78a. Section 78c is provided with extend flaps 78c' and 78c'' which are marked off from the section 78c by suitable score lines.

The other flaps 76, 77 and 79 are similar to flap 78 just described.

As shown the flaps are so cut that the reinforcements when folded into position meet each other at the corners in a miter joint.

Extending around the edge of the section 75 are the four strips of metal 80, 81, 82, and 83 each formed with predetermined bending line 80a, 81a, 82a, and 83a, and so secured to the blank 70 that these bending lines are superposed

over the double score defining the section 75. As shown these predetermined bend lines are of the type as described in my copending application for Predetermined bend line, Serial No. 45,710, 5 hereinbefore referred to.

In setting up the panel, each of the flaps is bent on the score lines to the position as shown in Figure 18. The metal strips are then turned on their bend line as shown at 82 in the same figure. In the set up position the extend flap 78c' is in contact with the extended flap 77c'', thus forming an added seal at the corner. Each of the four corners is thus double sealed in this manner.

Now referring to Figures 20, 21, and 22 there is shown a type of panel similar to that from the blank of Figure 17, except that the outer sections of the flaps are turned inwardly toward the center of the panel instead of outwardly toward the flange. Also the auxiliary flaps on the sloping portions have been omitted as have the metallic strips along the bending line. Thus the blank 90, of Figure 20 conforms to the blank 70 of Figure 17, except that the end sections 76f, 77f, 78f, and 79f of the flaps of Figure 20 are trimmed on their edges to be folded inwardly instead of having the reentrant cut as shown on the outer sections 76d, 77d, 78d, and 79d of Figure 17. When the blank of Figure 20 is folded 30 into shape as shown in Figure 21, the flap sections 76f, 77f, 78f, 79f, may be secured to the section 75 of the blank by adhesive or other means such as the rivets 91, shown in Figure 21.

If the panel such as that shown in Figure 20 is to be used as a door it may be provided with the slots 11a, 11b, and 11c for attaching a hinge portion to the door member, with the fastening means for the hinge within the side reinforcing member. The opening 11d provides means for mounting a handle within the other side reinforcement with the handle protruding through the opening 11d.

While in these forms of panel having a reinforcing member whose section is triangular, I have shown a right triangle whose right angle is toward the outer edge of the panel, it is quite obvious that by minor changes such as would be apparent to one skilled in the art, I can modify the flanks and the resulting panels so that the right angle is toward the center of the panel, or so that none of the angles of the triangle are right angles. Moreover, I can flatten off the apex of the triangle so that the hollow reinforcement is in cross section the form of a trapezoid, or a trapezium.

Thus, in Figures 23 and 24, I have shown a modification of the blank of Figure 20 to form a reinforcement wherein the cross section is that of a trapezoid having the inner wall 100c, 101c, 102c, 103c perpendicular to the walls 100b, 100d; 101b, 101d; 102b; 102d; 103b, 103d; and the panel face 99. This trapezoid section as shown in the Figures 23 and 24, starts at the edge of the panel, and does not have a flange around the panel as in Figures 20 and 21; but it will be readily understood that such a flange could be provided.

In Figures 25 and 26, I have shown a form of panel similar to that of Figure 11, except that side wings 110 and 111 made respectively from the flaps 110a, 110b, and 111a, 111b of the blank 109. With wings such as are shown at 110 and 111, the reinforced panel of the present application may be used with a form of metal facing

120 as shown in my copending application for Drawer, Serial No. 45,711, hereinbefore referred to for use as an improved modification of the filing drawer disclosed in my Patent 1,946,516.

In Figure 26, it will be noted at 112 and 113, that the flap 110a is cut back into the flap 114 and flap 111b is cut back into flap 115 a distance substantially equal to the thickness of the material. In this way, after the panel is bent into shape, as shown in Figure 25, the flap 110b will be flush with flap 116; and flap 111b will be flush with flap 117.

It will of course be understood that the other forms which I have shown may be provided with side wings in a manner similar to that shown in Figures 25 and 26.

Moreover, it will be further understood that the particular forms described in this application are by way of illustration and that many changes in details may be made without departing from the scope and spirit of my invention as set forth in the attached claims.

Now having clearly described my invention so that it may be readily understood by one skilled in the art, I claim:

1. A panel comprising a blank of sheet material having fold lines along which said blank is manually foldable, flaps integral with said blank foldable to form reinforced edges of hollow construction for said panel; extensions on one of said flaps and slots on an adjacent flap arranged to interlock with the flaps in the folded position; whereby when one of said flaps is secured in position as a hollow reinforcing member, the other of said flaps is also secured in position as a hollow reinforcing member.

2. A panel comprising a blank of sheet material having fold lines along which said blank is manually foldable, flaps integral with said blank foldable to form reinforced edges of hollow construction for said panel; extensions on one of said flaps, and slots on an adjacent flap arranged to interlock with the flaps in the folded position; whereby when one of said flaps is secured in position as a hollow reinforcing member, the other of said flaps is also secured in position as a hollow reinforcing member.

other of said flaps is also secured in position as a hollow reinforcing member, a strap secured to the extremity of one of the flaps and a slot in the same flap for admitting said strap.

3. A panel comprising a blank of sheet material having fold lines along which said blank is manually foldable, flaps integral with said blank foldable to form reinforced edges of hollow construction for said panel; extensions on one of said flaps and slots on an adjacent flap arranged to interlock with the flaps in the folded position; whereby when one of said flaps is secured in position as a hollow reinforcing member, the other of said flaps is also secured in position as a hollow reinforcing member; and extensions on one of said flaps arranged to form end walls on adjacent hollow reinforcing members.

4. A panel comprising a blank of sheet material having fold lines along which said blank is manually foldable, flaps integral with said blank foldable to form reinforced edges of hollow construction for said panel; extensions on one of said flaps and slots on an adjacent flap arranged to interlock with the flaps in the folded position; whereby when one of said flaps is secured in position as a hollow reinforcing member, the other of said flaps is also secured in position as a hollow reinforcing member; and flanges protruding outwardly from said reinforcements.

5. A panel comprising a blank of sheet material having fold lines along which said blank is manually foldable, flaps integral with said blank foldable to form reinforced edges of hollow construction for said panel; extensions on one of said flaps and slots on an adjacent flap arranged to interlock with the flaps in the folded position; whereby when one of said flaps is secured in position as a hollow reinforcing member, the other of said flaps is also secured in position as a hollow reinforcing member; flanges protruding outwardly from said reinforcements; and a metallic U-shaped base member bent around the periphery for enfolding said protruding flanges.

PHILIP ZALKIND.
